DOORCHECK

Filed July 15, 1929

FIG. 2.

FIG. 3.

FIG. 4.

INVENTOR

Thomas S. Williams

BY Frank D. Gray

ATTORNEY

FIG. 1.

UNITED STATES PATENT OFFICE

THOMAS S. WILLIAMS, OF DALLAS, TEXAS

DOORCHECK

Application filed July 15, 1929. Serial No. 378,419.

My invention has reference to certain new and useful improvements in door checks, and while designed more particularly for use with screen doors which are ordinarily provided with a spring for closing the door, I regard my improved structure as adaptable for general application including swinging members other than doors which it is desired to check in its closing movement by providing a stationary member upon the casing or stationary frame to receive the impact of the check carried on the swinging element.

It is an object of my invention to mount a cylinder upon the door, preferably upon the upper frame piece of a screen door, mounting the cylinder laterally on the door with its axis parallel with the plane of the door, and its open end facing the inner vertical piece of the door jamb, when the door is closed. It is a special object of my improvement to mount the moving piston adjacent the open end of the cylinder where the piston may receive the inward thrust of the stationary or fixed arm mounted on the casing and thus tend to drive the piston within the cylinder in a direction nearly parallel with the plane of the door, toward the final movement of the door as it nears the jamb.

It is a further object of my invention to mount my open ended cylinder adjacent the hinge and laterally upon the door, providing a piston within the cylinder adjacent the open end thereof and having an outer flat surface to serve as a buffer plate to receive the thrust of the outer end of a stationary arm fixed in the door jamb, the cylinder being relatively short compared with the swinging movement of the door and having no projecting parts from either the open or its closed end.

A further object of my invention provides for the use of a cylinder in which the moving piston will operate against a compression spring and pneumatic pressure.

I further provide other improvements in details of construction facilitating mounting of the cylinder upon the door, and of adjustment of the force of the spring within the cylinder, as well as automatic control of the pneumatic pressure therein.

Other objects and advantages of the in-

vention will appear as the description proceeds, the inventive idea being set forth in the appended claims, and illustrated in the accompanying drawings in which:

Figure 1 is a plan view of a door and door casing and a compression cylinder shown in horizontal section, together with related parts;

Figure 2 is an end elevation of the cylinder as it would appear in the direction of the arrows indicated in the plane of the line 2—2 of Fig. 1;

Figure 3 is a sectional detail of a modified form of the mounting mechanism for the cylinder, and

Figure 4 is a detail end elevation of the cylinder with parts broken away.

Like reference numerals will indicate like parts in the several views. I have illustrated the door 5 hinged at 6 to the door frame 7, the door being shown partially closed in full lines in Fig. 1. The door will ordinarily be urged to the closed position by spiral spring 8 detachably connected to the hooks 9 and 10 mounted on the door and door frame, preferably at the bottom of the door, such position preventing the tendency of a possible slight slam when both spring and check are on the same end of the door.

The door check comprises a main cylinder 11 having its open end 12 directed towards the hinge side of the casing and mounted laterally on the door with its axis parallel with the plane of the door. Within the cylinder 11 a cup piston 13 having a peripheral flange 14, is movable axially as governed by impulses applied to the surfaces of the piston. On the outer surface of the piston 13 is attached a circular plate guide member 15 having peripheral flanges 16 which on their outward movement will engage the inturned flange 17 at the open end of the cylinder, and thereby be retained within the latter.

The outer surface of the circular member 15 will usually be formed of metal of sufficient strength to resist wear of a metal arm moved across the same under strong pressure. The main piston 13 will be formed of more or less flexible material, such as leather whose peripheral flanges 14 will follow the

wall of the cylinder 11 when moved within the same in action quite analogous to the action of a pump piston. On the inner surface of the piston 13, opposite the metal plate 15, 5 a follow plate 18 engages the transverse portion of the piston and is positioned within the flange 14. This plate 18 is metallic and will serve to receive the thrust of a compression spring 19 whose opposite end 20 10 will engage the apertured head 21 of the cylinder.

The cylinder 11 is mounted laterally upon the door by means of a bracket 22 of L form which, as shown in Fig. 1, has an inturned 15 arm 23 supporting the wall of the cylinder, and which may be secured to the frame of the door by fasteners such as screws 24. The outer arm 25 of the bracket 22 will be secured to the cylinder head 21 by fasteners such as 20 rivets 26, and will be provided with an apertured centrally positioned conical portion 27 providing an inner socket 28 to receive loosely therein a valve ball 29 which may cover the opening 30 in such conical portion 27. The 25 head 21 is also provided with two spaced apertures 31, one being slightly above the other and both arranged opposite the base of the socket 28, for permitting air to escape from the cylinder, and thereby force the ball 30 29 against the opening 31.

One end of the spring 19 engages the follow plate 18 upon the piston and the opposite end rests against the inner surface of the cylinder head 21, so that the spring urges the piston 35 forward to its normal position when relieved from the force of the plunger 36. A screw 32 is provided which is inserted through the arm 25 and may be adjusted in 40 said arm, and in the apertured head 21 to permit varying amount of leakage of air to permit a slower or faster movement of the piston toward the head.

In the form of mounting for the cylinder upon the door, I may use the modified form 45 of bracket shown in Fig. 3, in which the bracket 33 has an outturned bracket 34 secured to the door by the same kind of fasteners 24, but whose mounting of the cylinder upon the bracket is correspondingly 50 modified. In both these forms of mounting the door check, the cylinder of the check is mounted with its axis parallel to the door itself, and with the open end of the cylinder 11 facing the door frame member strip 35, when 55 the door is in its closed position. This modified form of bracket is used for attachment to the apertured cylinder head 21, and is provided with the conical portion 27 and the adjusting screw 32, as in the other form. This 60 makes feasible the highly efficient application of my improved door check which shall result in the greatest compact relation of the cylinder 11 and a stationary plunger 36 which is mounted on the strip 35 and extends 65 into the direct path of axial movement of the

piston member 15 as the door nears its closed position, as clearly indicated in Fig. 1.

The plunger 36 is preferably mounted upon the frame strip 35, and may be securely so positioned by insertion of its smaller end, 70 which may be screw-threaded, into the strip, or otherwise attached thereto, leaving the outward-extending end 37 projecting at right angles to the strip 35, to axially engage the metal member 15 of the piston 13. The outer end of the plunger 36 has a roller 38 thereon to provide easy movement along such surface 75 15, or a smooth, rounded end thereof may be provided of hardened metal to take the place of the roller.

As the door 5 swings into closed position, as by the stress of the spring 8, the plate 15 upon the piston 13 will contact the outer end of the plunger before the door is closed, the plunger 36 remaining in rigid position in all 80 positions of the door. As the plunger end strikes the plate, the piston 13 will move toward the apertured head 21 of the cylinder, inner movement of the door tending to compress the air in the cylinder as well as the 85 spring 19. When the door reaches its closed position, the piston will have traveled axially toward the head 21 at least half of the length of the pneumatic cylinder, and mounting laterally my cylinder of relatively large 90 radius and short length upon the door permits a relatively short stroke of the piston and by the use of a short cylinder. It is to be understood that the flanges 16 guide the 95 axial movement of the piston, and brace the latter against oblique movement.

Pneumatic action of the piston 13 results from leak-proof fastening of the rivets 26, very slight leakage of the screw 32 in the plates, and closure of the port 30 by the ball 29 under air current from the apertures 31. The normal position of the ball, when not under the force of air pressure, is that nearly 100 covering the lower port 31.

The continuous mounting of the cylinder 11 on the door 5 and moving bodily with it in opening and closing, serves to cause the cylinder to move from or approach the plunger 36, and so provides the very advantageous 110 mounting of the check cylinder adjacent the door hinge—a relation not requiring relative movement of the check parts over a very large distance. Further, the side mounting of the cylinder 11 on the door permits the use of such a check of relatively small size, even having a diameter slightly less than the distance between the door 5 and another 115 parallel with it. This arises from the fact that the length of the check need not occupy the space between the doors. The roller 38 or rounded end assumes a different position on the plate 15, as the latter moves at right angles or obliquely to the plunger 36, and this 120 causes movement of the plunger end upon the plate.

While it is my purpose to mount the cylinder 11 of the check upon the upper end of the door, it is appreciated that it may be mounted on the lower end or on an intermediate transverse bar of the door, but in all cases

5 will be mounted on the inner surface of the door and not very far from the hinge edge of the door. In all cases, I propose to contact the roller 38 by the plate 15 of the plunger, though it is to be understood that any suitable means may be used on the outer end 37 of the plunger, whether a bearing such as the roller 38 or a stationary rounded end on said plunger is in direct contact with said plate.

10 15 A further advantage arises from mounting the cylinder on the door rather than on the door frame, and which advantage results from the piston 13 receiving the stationary plunger 36 thereon, and this advantage especially includes the convenience of storing the main part of the check together with the door when the latter is removed from its frame at the proper season. The door carries the cylinder 11 with it when hung or stored. In the latter case, the plunger 36 may remain on the strip 35, or may very readily be removed, if desired.

20 25 30 Various modifications will suggest themselves which may be utilized without departing from the spirit of the invention or sacrificing any of its advantages, and are contemplated.

35 Having thus described and illustrated my invention, what I desire to secure by Letters Patent, is:—

1. A door check of the class described comprising a pneumatic cylinder having an open end and an apertured closed end mounted on the door, a piston within the cylinder, a buffer spring between the piston and the closed end of the cylinder, a face plate mounted on the piston on the side thereof facing the open end of the cylinder, a support bracket secured to said closed end and the door and having a valve operating in conjunction with said apertures and a stationary plunger mounted on the door frame and having an outwardly extended end directed toward the open end of said cylinder to contact the said face plate to receive the shock when the door swings to closed position.

40 45 50 55 60 65 2. A door check including a cylinder mounted horizontally and laterally on a door and having an open end and a closed end having vertically arranged apertures, a piston movable therein and having a metal surface facing toward the open end of the cylinder and a metal surface on its opposite side for contact with a spring, a compression spring between the piston and said closed end, a rigid bracket attached to the door and to said closed end and having an apertured cone therein forming an inner ball socket alining with the apertures of said closed end, and a

stationary horizontal plunger mounted on the door frame and directed toward said open end to contact said metal surface of the piston nearest the open end to receive the shock of the door, when the door closes.

70 75 80 85 90 95 3. A door check including a cylinder mounted laterally and horizontally on the door and having an open end and a closed end having centrally and vertically spaced apertures, a piston movable therein and having metal end surfaces, a compression spring between the piston and said closed end, a rigid support bracket having an arm attached to the door and another arm secured to said closed end and having an apertured cone therein forming an inner socket alining with the apertures of said closed end, a ball seated in said socket and normally by gravitation covering the lower of said vertically arranged apertures, but under air current from the latter induced by abnormal pneumatic pressure in the cylinder, forcing the ball into said socket thereby closing the aperture in the said cone, and a rigid horizontal plunger member mounted on the door frame and extending outward in the direction of the said piston when the door nears its closed position, whereby the lower of said vertical apertures is closed by the ball when the plunger is out of contact with the piston, but the socket aperture is closed when the door is nearly closed.

100 In witness whereof, I have hereunto set my hand this 10th day of July A. D. 1929.
